Attorney

UNITED STATES PATENT OFFICE.

WILLIAM H. DOUGHTY, OF SPRINGVALE, MAINE.

HEEL.

Application filed December 1, 1923. Serial No. 677,983.

To all whom it may concern:

Be it known that I, WILLIAM H. DOUGHTY, a citizen of the United States, residing at Springvale, in the county of York and State 5 of Maine, have invented certain new and useful Improvements in Heels, of which the following is a specification, reference being had to the accompanying drawings.

This invention relates to heels for shoes, 10 boots, slippers, and the like, and has for its object the provision of a novel heel construction involving the use of an inserted layer of rubber whereby the finished heel will have all of the advantages of the ordinary well known rubber heel while being 15 cheaper inasmuch as the layer exposed to wear consists of a leather lift.

An important and more specific object is the provision of a heel of this character in 20 which provision is made for permitting detachment of the leather lift when the same becomes worn out, the worn out lift being replaced by a new one of identical construction capable of being produced at extremely 25 low cost.

It is well known that the ordinary rubber heel quickly becomes worn either at the back or at the edge so that it throws the shoe out of proper line, causing improper 30 walking and unsightliness. With this fact in view I have designed the present construction in which the rubber portion of the heel is inserted between the heel portion of the shoe and a leather lift, the latter taking 35 up the wear so that the rubber itself is not affected in any way.

An additional object is the provision of a heel constructed of this character which will be very simple and inexpensive in manufacture, capable of renewal without tools 40 and by those unskilled in the art, and which will, moreover, be highly efficient, satisfactory and durable.

With the above and other objects and advantages in view, the invention consists in the combination and arrangement of parts to be hereinafter more fully described and claimed and illustrated in the accompanying drawings in which—

50 Figure 1 is a side elevation of a portion of a shoe and a heel constructed in accordance with my invention, a portion of the heel being in section.

55 Figure 2 is a bottom plan view of the rubber insert showing the fastener elements carried thereby.

Figure 3 is a similar view of the leather lift.

Figure 4 is a section through a modification.

Referring more particularly to the drawings, the letter A designates a portion of a shoe having its heel portion equipped with a layer or lift B of leather in accordance with the usual practice. In carrying out my invention I provide a layer or insert 10 of rubber which is formed with holes 11 through which extend the shank portions 12 of snap fastener elements formed with heads 13 projecting beyond or below the lower surface of the insert, and which are further formed or provided with flanges 14 bearing upon the upper surface of the rubber insert. Any desired means may be employed for securing this rubber insert to the underside of the leather lift B, though in actual practice a convenient method is to utilize nails 15 of conventional pattern which are driven through the rubber insert into the lift B and sole portion of the shoe. 70 Ordinarily it is a practice to provide rubber heels and kindred devices with washers embedded therein and having holes through which the securing nails pass, and in accordance with this general practice, I prefer to use washers or disks 16 embedded in the rubber insert during the manufacture thereof for an equivalent purpose so that there will be no likelihood of the nails tearing out. 80

Below the rubber insert I employ a lift 17 of leather which naturally must have the same configuration as the rubber insert and the body of the heel itself and which is formed with suitable recesses within which 90 are located snap fastener elements 18 mounted or secured in any desired manner such as for instance by prongs, by cementing or the like.

In assembling the heel, the insert 10 is 100 fastened to the leather lift B of the heel, and possibly to the sole portion of the shoe by means of the nails 15 which are driven through the insert and through the holes in the disks or washers 16. It will be observed 105 that the heads 13 of the snap fastener elements project below the lower surface of the rubber insert so that when the leather lift 17 is applied the snap fastener elements 18 carried thereby may be forced onto the heads 110 13 of the snap fastener elements carried by the rubber lift. When the leather lift 17

becomes worn out it is obvious that it may be quickly and easily replaced by prying it off with a screw-driver, chisel or other similar tool, the heads 13 of the fastener elements carried by the rubber insert being undamaged. In view of the fact that the rubber insert itself never comes in contact with the ground or other surface walked upon, it is apparent that it is not subject to wear and 10 that it may last indefinitely, the only replacement being the leather lift.

In Figure 4 I have illustrated a slight modification in which the same general principle is involved. However, in this form I 15 have illustrated the employment of a snap fastener element 19 which is let into the rubber insert and which cooperates with a mating element 20 let into the bottom leather lift. It will be seen that the only difference 20 is that in this case cement or other means must be employed for holding the snap fastener element 19 within or associated with the rubber insert as the element 19 is not equipped with an elongated shank passing 25 through the entire insert and terminating in a flange bearing upon the top surface thereof, as in the first described form. As a matter of fact, there is no limitation contemplated as to the exact arrangement or type 30 of snap fasteners used as it will be obvious to the trained mind that they may be trans-

posed and that various fasteners of different constructions may be used with equal advantage, especially inasmuch as the essential feature is the quick replacement, without tools, in the event that the lowermost or 35 wear receiving lift becomes worn out.

I claim:

A shoe heel including upper, intermediate and lower sections, snap fastener elements 40 carried by the intermediate section and each including an elongated shank extending entirely through the intermediate section and terminating at its upper end in an enlarged base bearing upon the top surface of the intermediate section, each shank terminating at its lower end in a ball head projecting below the bottom surface of the intermediate section, securing elements fastening the intermediate section to the top section and to 45 the shoe to which the heel is applied, and snap fastener sockets recessed into the lowermost section and coacting with said ball heads for holding the lowermost section onto the intermediate section, the enlarged bases operating to prevent tearing of the first-named 50 fastener elements through the intermediate section.

In testimony whereof I hereunto affix my signature.

WILLIAM H. DOUGHTY.
